UNITED STATES PATENT OFFICE.

BERTILL CARL PETTERSON, OF MEMPHIS, TENNESSEE.

WINDOW-GUARD.

1,378,378.

Specification of Letters Patent.

Patented May 17, 1921.

Application filed March 26, 1920. Serial No. 369,058.

To all whom it may concern:

Be it known that I, BERTILL CARL PETTERSON, a citizen of the United States, and a resident of Memphis, in the county of Shelby 5 and State of Tennessee, have invented a new and useful Improvement in Window-Guards, of which the following is a specification.

My present invention relates generally to window guards and more particularly to 10 guards in the nature of curtains, my object being the provision of an automatically dropping curtain for use in connection with store or display windows and normally controlled and held in ineffective position by 15 means shiftable under excessive vibration to release the guard for movement downwardly to effective position covering the window space.

A further object of my invention is the 20 provision of a slatted guard screen which may be normally held in an upper practically concealed position together with means for locking the same in lower effective position covering the window space, the said 25 locking means automatically acting when the screen or curtain drops.

With these general objects in mind, further objects and the resulting advantages of my invention will be readily apparent from 30 the following description which refers to the accompanying drawings, forming a part of this specification and wherein,

Figure 1 is a front elevation of a display window provided with my improvements, 35 showing the same in upper inactive position,

Fig. 2 is a similar view with the screen or curtain dropped and secured in effective position,

Fig. 3 is a vertical section taken on the line 40 3—3 of Fig. 1,

Fig. 4 is an enlarged vertical section adjacent to the lower portion of the curtain or screen in the upper inactive position,

Fig. 5 is a detail horizontal section taken 45 on the line 5—5 of Fig. 2,

Fig. 6 is a detail perspective view of the supporting bracket, and

Fig. 7 is a detail section through one of the rock bar carriers of the curtain or screen. 50 Referring now to these figures and particularly to Figs. 1 and 2 illustrating show windows 10, I mount within these show windows for the purposes of my invention, a pair of side uprights 11, preferably of cylindrical form, to the upper ends of which the

upper cross bar 12 of my improved guard screen is secured at its opposite ends. The screen includes a lower cross bar 13 and a series of parallel slats 14 between the bars and connected to the latter by lazy tongs 15 60 so that the slats are movable freely with respect to one another and the two cross bars 12 and 13 between the upper inactive position of Fig. 1 where the screen is collapsed and the active position of Fig. 2 where the 65 screen is extended or dropped.

At its opposite ends the lower cross bar 13 has vertically spaced roller carrying brackets 16, each of which supports rollers 17 in engagement with one of the uprights 70 11 at diametrically opposite points, so as to effectively guide the lower cross bar in its downward movement and prevent the same from binding.

Intermediate its ends and upon its outer 75 face the lower cross bar 13 has a recess 18 adapted to receive the head 19 of a bolt 20 which acts as a latch and is carried by a latch plate 21 suspended by means of a chain 22 between the guard screen and the 80 window glass 23 as particularly seen in Fig. 4. The outer end of the latch bolt 20 is concaved to receive one end of a key 24 whose opposite end is adapted to bear against the inner surface of the window glass 23 and 85 thus brace the latch plate 21 against the outer face of the guard screen and hold the inner head 19 of the bolt in the recess 18 of the lower cross bar 13 to prevent the screen from dropping. At its outer end the 90 key 24 has an eye 25 to which one end of a chain 26 is mounted, the opposite end of this chain being connected to a trip arm 27 whose upper weighted end 28 normally rests against the window glass 23 in the inactive 95 position shown in Fig. 3. One end of the trip arm 27 is pivotally mounted in a bracket 29 secured to an attaching block 30 which is in turn fastened to the inner surface of the window glass 23 at or about the 100 center of the window as by means of any suitable adhesive or cement, the pivot support of the trip arm 27 adapting the latter to swing inwardly and downwardly in case of excessive vibration of the window glass 105 23, so that during such movement it will pull downwardly upon the chain 26 and thus jerk the bracing key 24 downwardly from the position shown in Figs. 3 and 4. This permits the latch plate 21 to swing toward 110

the window glass 23 and away from the guard screen, withdrawing the inner head 19 of the latch plate from the recess of the lower cross bar 13 so that the screen is thus 5 free to drop in guided relation across the window opening and to the effective position shown in Fig. 2.

It is intended that the trip arm 27 shall be so positioned in practice as to avoid its 10 accidental movement or its movement under ordinary vibrations of the window caused by adjacent vehicular traffic or the mere placing of hands against the window glass and still be sufficiently sensitive to operate upon any 15 vibration whose extent is such that it endangers the safety or integrity of the glass. For this purpose the lower pivot of the trip arm 27 is preferably carried by an adjustable plate 31 as seen in Fig. 6, mounted to slide 20 in grooved walls 32 of the bracket 29 toward and away from the window glass, this adjusting plate being secured in selected position by a clamping screw 33 extending through its slots 34 and threaded into the 25 bracket 29.

I further propose to effect automatic locking of the screen when it drops and for this purpose I provide the lower portion of the same frame with socket members 35 containing locks somewhat similar to the locks 30 of desks for covers adapted to receive the lower free ends of rack bars 36 depending from the lower cross bar 13 and preferably supported with their upper portions movable 35 through brackets 37 carried by the said cross bar, above which the upper ends of the rack bars are headed. These brackets or holders 37 preferably have ratchet levers 38 adapted to engage the rack bar 36 and 40 thus permit the rack bars to yield automatically when their lower ends have entered the keeper sockets 35 in locked relation as in Fig. 2, and in this way impose a gradual check to the lowering movement of the 45 screen without placing the burden of its impact against the locking sockets.

To prevent excessive lowering movement of the screen and support the same in its lowered position in such manner that it can 50 be readily raised, each of the several toggle arms 15 is provided with an extending end provided with an angular portion 40 with which the next adjacent arm comes into engagement which is still in angular relation 55 and thus the several arms of the toggle levers or lazy tongs will be readily movable to the collapsed or folded position when the screen is raised.

It is obvious that my invention as thus 60 constructed and adapted to operate may be utilized for the protection of store, show windows, and in fact display windows of various characters, and will in its upper normal or collapsed position be practically

invisible through its location behind either 65 the upper side portions of the window or a small drop curtain with which store and show windows are commonly provided.

It is also obvious that my invention will be effective for the purposes described and 70 particularly where the show or display window has been broken with a view to entrance in this way to a store, my improved screen will in its lower position cover the broken window in such a way as to prevent entrance 75 and defeat the purposes for which the window was broken.

I claim:—

1. The combination with a window frame having a glass, of a guard screen extensible and collapsible within the window to cover the said opening and means connected to the window glass and controlled by the vibration thereof for normally holding the screen in folded or collapsed position. 80

2. The combination with a window frame having a glass, of an extensible guard screen normally collapsed at the upper portion of the window and movable by gravity to extended position downwardly across the window opening, and means connected to the window glass and controlled by the vibration thereof for normally holding the guard screen in collapsed position. 90

3. A window guard of the character described including uprights, upper and lower cross bars of which the upper cross bars are secured to the uprights and the lower cross bar has sliding connection therewith, a series of slats parallel with and between the cross bars, toggle levers connecting the slats and cross bar, trip controlled means for normally holding the screen in upper collapsed position, and means for locking the screen in lowermost position. 100

4. A window guard of the character described including uprights, upper and lower cross bars of which the upper cross bars are secured to the uprights and the lower cross bar has sliding connection therewith, a series of slats parallel with and between the cross bars, toggle levers connecting the slats and cross bar, trip controlled means for normally holding the screen in upper collapsed position and means for locking the screen in lowermost position, said last-named means including rack bars carried by the lower cross bar and yieldable with respect thereto and ratchet levers carried by the lower cross bar and engaging the rack bars. 110

5. The combination with a display window having a glass, of a gravity guard screen collapsible in the upper portion of the display window, a latch plate engaging a portion of the screen to normally hold the same in collapsed position, a key supporting the latch plate and braced between the same and the window glass, and a trip 125

arm movable by excessive vibration of the window glass and connected to the key for displacing the latter upon movement thereof.

6. The combination with a display window of an extensible guard screen normally held in collapsed position in the upper portion thereof and means for controlling the screen including latch means engaging the screen, a key normally braced between the latch means and the window glass, a bracket supported by the window glass, and a weighted trip arm pivoted to the bracket and normally resting against the window glass, said trip arm being connected to the key for displacing the latter upon swinging movement of the trip arm.
- 5 10 15

7. The combination with a display win-

dow of an extensible guard screen normally held in collapsed position in the upper portion thereof and means for controlling the screen including latch means engaging the screen, a key normally braced between the latch means and the window glass, a bracket supported by the window glass, and a weighted trip arm pivoted to the bracket and normally resting against the window glass, said trip arm being connected to the key for displacing the latter upon swinging movement of the trip arm, and means adjustable on the bracket toward and away from the window glass and supporting the pivot of the trip arm, for the purpose described.

BERTILL CARL PETTERSON.
